UNITED STATES PATENT OFFICE.

JOHN P. FINDLEY, OF CROSSVILLE, ALABAMA.

COTTON-CHOPPER.

1,140,144.

Specification of Letters Patent.

Patented May 18, 1915.

Application filed March 10, 1914. Serial No. 823,745.

To all whom it may concern:

Be it known that I, the undersigned, JOHN P. FINDLEY, a citizen of the United States, residing at Crossville, in the county 5 of Dekalb and State of Alabama, have invented certain new and useful Improvements in Cotton-Choppers; and I do hereby declare the following to be a full, clear, and exact description of the invention, such as 10 will enable others skilled in the art to which it appertains to make and use the same.

This invention relates to cotton choppers and more particularly to those of the straddle row type.

15 One of the objects of this invention is the provision of means for throwing the dirt away from the rows of the cotton at each side thereof, then chopping out the step and finally throwing the dirt toward the rows 20 in successive operations.

A further object of my invention is to furnish a means for removing the superfluous plants from a row and to evenly space those plants that are left in the said row.

25 A further object of this invention is to provide improved means for throwing the machine into and out of gear by a lever within easy reach of the operator of the machine, whereby the chopping plates may 30 be checked in their movement, thus avoiding the destruction of plants desired to remain standing.

A still further object of this invention is 35 to provide an improved construction of the working parts whereby the same are capable of ready adjustment relative to each other for taking up the lost motion occasioned by the wear upon the parts.

With these objects in view the invention 40 consists in the improved construction, combination and arrangement of parts herein-after fully described and afterward specifically claimed.

In the accompanying drawings, which 45 illustrate an approved embodiment of my invention, Figure 1 is a top plan view of the machine showing the same in its complete form ready for operation. Fig. 2 is a side view of the same showing the chopping 50 plates in vertical position and the position of the gear lever in proximity to the handles of the machine. Fig. 3 is a fragmentary detail view showing the manner of adjustably mounting the ends of the revolving arms. 55 Fig. 4 is a detail sectional view taken on

line 4—4 of Fig. 3. Fig. 5 is a fragmentary detail view partly in section taken on line 5—5 of Fig. 3.

Referring to the drawings the frame consists of the side rails 1 and 2 the forward ends of which converge as at 3—3 and meet to form the tongue 4 provided with the clevis 5 at the end thereof for the reception of the single tree or double tree 6.

Arranged at the rear ends of the side rails 1 and 2 is the rear rail 7 one end of which projects for a distance beyond the same as at 8, and in the upper face of the projecting end 8 are the spaced notches 9 and 10. Secured centrally upon the rail 7 by the bolts or other securing means 11 is the bracket 12 of the bearing 13. Transversely mounted within the frame at a point in advance of the rear rail 7 is the cross rail 14 and secured centrally thereupon by the bolts or other securing means 15 is the bracket 16 provided with the horizontal slot 18. Upon the rails 1 and 2 of the frame and forwardly of the cross rail 14 and secured thereon 75 by the bolts 19 are the brackets 20 of the bearings 21, and mounted within the bearings 21 and extending transversely of the frame is the axle 22 upon the ends of which are the master wheels 23 having arranged 80 within the hubs 24 suitable pawl and ratchet mechanism not shown for revolving the axle 22 in a forward direction only.

Adjustably arranged upon the axle 22 at a point approximately intermediate the ends 90 thereof is the bevel gear 25 having its hub 26 secured to the axle 22 by a set screw 27.

Arranged longitudinally within the frame is the shaft 28 the rear end of which is suitably journaled within the boxing 13 upon 95 the rear rail 7 and retained therein by collars 29 secured to the shaft 28. The forward end of the shaft 28 projects beyond and is suitably journaled in a boxing, the said boxing being slidably mounted in the 100 horizontal elongated opening 18 in the bracket 16 upon the cross rail 14 and there is mounted upon the free end of the shaft 28 the bevel gear 30 for meshing with the bevel gear 25 upon the axle 22 whereby to 105 revolve the shaft 28 with the axle.

Arranged upon the shaft 28 are the hubs 31 secured to the shaft 28 by set screws 32, the hubs 31 being each provided with the oppositely extending arms 33 having arranged 110 in the free ends thereof slots 34, and extending from each of the opposing arms 33 are

the chopping plates or knives 35 provided at each of their ends with projections 36 upon the outer faces of which are arranged rectangular lugs 37 adjustably mounted 5 within the slots 34 of the arms 33 and retained in their respective adjusted positions by a set screw 38.

For throwing the bevel gear 30 into and out of engagement with the bevel gear 25 10 there is provided the lever 40 at the right hand side of the machine, the lever 40 having a portion of the forward end thereof bent inwardly in right angular direction to provide the arm 41 and then forwardly bent 15 to provide the arm 42, the arm 42 being pivotally connected to the clamp 43 surrounding the axle 22 and retained thereon in adjusted position by the collars 44 at each side thereof, the collars 44 being secured to the 20 axle 22 by set screws 45. The rear end of the lever 40 is bent upwardly to provide the arms 46 and upon the upper end of which is the hand grip 47, in close proximity to the operator of the machine. At the bent portion 25 between the arms 41 and 42 of the lever 40 is pivotally connected the link 48, which link is also pivotally connected at its opposite end to the clamp 49 surrounding the shaft 28, and retained thereon by the collars 30 50 at each side thereof. Secured to the rails 1 and 2 of the frame by the bolts 51 are the handles 52 provided with braces 53 extending therefrom and attached to the rails 1 and 2 of the frame, the handles being also 35 provided with the brace rods 54, the right hand handle 52 being adjacent to the hand grip 47 of the lever 40 in order that the same may be in easy reach of the operator. The lever 40 is designed to engage the respective 40 recesses 9 and 10 of the projection 8 of the rear rail 7 for holding the gear 30 in or out of engagement with the gear 25 of the axle 22.

Secured upon the rear rail 7 of the machine by bolts 55 are the arms 56 provided at their lower ends with the feet or cultivators 57 for throwing the dirt toward the rows of cotton.

At the forward end of the machine and secured upon the tongue 4 thereof by the bolts 58 is the bracket 59 upon the lower end of which is revolvably mounted the oppositely disposed and obliquely arranged disks 60 50 designed to throw the dirt away from the 55 rows of cotton.

During the chopping operation the machine is designed to straddle the rows of cotton, the disks 60 throw the dirt away from the rows of cotton at each side thereof, and 60 the revolving chopping blades 35 following thereafter chop the step between the hills of

cotton at intervals along the narrow strip of land left by the disks 60, while the cultivators 57 following the chopping blades 35 throw the dirt back again toward the cotton 65 and thus cultivate the same during the chopping or thinning operation. The lever 40 and its connections with the revolving shaft 28 carrying knives 35 is designed to move the forward end of the shaft 28 which is 70 slidably mounted to the slot 18 arranged in the bracket 16 upon the cross bar 14 and thus moves the gear 30 upon the forward end of the shaft 28 toward or away from the gear 25 upon the axle 22 when it is desired 75 to throw the machine into and out of gear, the lever 40 being retained in either of the respective positions by its engagement in the notches 9 and 10 in the member 8.

It is to be noted that the gear 25 on the 80 axle 22, the sleeve 43 in which the lever 40 is mounted, the hub 31 of the chopping plates 35, and the plates 35 relative to the arms 33, are all adjustably mounted upon their respective supports, whereby all of 85 the parts are held in accurate and efficient engagement with each other and lost motion is wholly obviated.

While I have here shown and described the preferred form of my invention, I 90 hereby reserve the right to make such alterations and variations therein from time to time as I may deem expedient and which will not depart from the spirit of this invention nor conflict with the scope of the 95 claim.

I claim:

In combination a frame, an axle journaled therein, a pair of wheels and an intermediate bevel gear on the axle, a longitudinal 100 shaft, a bearing in the frame for the rear end of the shaft, a bearing for the front end of the shaft having a horizontal slot to receive the front journal of the shaft, a bevel gear on the shaft adapted to engage the 105 bevel gear on the axle, a chopping head on the shaft, a clamp on the axle, a clamp on the shaft, an angular lever pivotally connected to the clamp on the axle, a link pivotally connecting the lever at its angle with 110 the clamp on the shaft, and a bar projecting laterally from the frame having notches in its face to receive and hold the lever in adjusted positions.

In testimony whereof I have signed my 115 name to this specification in the presence of two subscribing witnesses.

JOHN P. FINDLEY.
